UNITED STATES PATENT OFFICE.

WILLIAM M. MYERS, OF HANNIBAL, MISSOURI.

BELT BUCKLE.

Application filed January 2, 1923. Serial No. 610,234.

To all whom it may concern:

Be it known that I, WILLIAM M. MYERS, a citizen of the United States, residing at Hannibal, in the county of Marion and State 5 of Missouri, have invented new and useful Improvements in Belt Buckles, of which the following is a specification.

This invention relates to buckles and has for its object the provision of a novel buckle 10 for use upon belts, straps, and the like, whereby the ends of the strap may be secured in a very efficient manner so as to positively prevent any slipping, the construction of the buckle being such that it is provided 15 with retaining means of peculiar formation and including a toothed element engaging the belt or strap for holding it rigidly associated with the buckle, the buckle being furthermore provided with a locking 20 bar operating along inclined slots.

An important object is the provision of a buckle of this character which is provided with means engaging the trousers in connection with which it is used whereby to prevent 25 the buckle from slipping up above the waist band as so frequently occurs in the use of the ordinary buckle.

An additional object is the provision of a buckle of this character which will be simple and inexpensive in manufacture, highly efficient in use, durable in service and a general improvement in the art.

With the above and other objects and advantages in view the invention consists in 35 the details of construction to be hereinafter more fully described and claimed and illustrated in the accompanying drawings, in which:

Figure 1 is a perspective view of my buckle looking at the rear side thereof and showing it disconnected from its strap,

Figure 2 is a longitudinal section showing the strap in place,

Figure 3 is a vertical cross section,

Figure 4 is a detail perspective view of the locking plate removed and

Figure 5 is a rear elevation of a modified form.

Referring more particularly to the drawings I have shown my buckle as comprising 50 a body 10 which is preferably longitudinally curved as shown, and which is formed with parallel flanges 11 at its edges, these flanges being provided with inclined slots 12 through which is slidably engaged a lock-

ing bar 13. This locking device is itself old and well known and I claim no novelty for it though it is illustrated as forming a part of my complete buckle. Though it is not absolutely essential it may be preferable to 60 make this body 10 slightly curved in cross section as well as longitudinally as illustrated in Figure 3.

The front of the body 10 is formed with an outwardly or forwardly pressed portion 65 14 of reduced size which has one edge constituting an abutment 14^a for one end of the strap 15, the strap lying in the cavity formed by the pressed out portion. The peculiar formation of the body defines a flange or 70 apron 14^b which has its rear surface co-extensive with the rear side of the strap.

The means for holding the strap associated firmly with the body consists of a plate 16 of spring metal which is formed at its ends with lugs 17 which are passed through slits 18 in one end of the flanges 11, and if preferred these lugs may be subsequently bent over or clinched, though as a matter of fact it is not essential. Such a structure however will strengthen the buckle and prevent any spreading of the flanges 75 with respect to each other. This plate 16 is preferably slightly curved as shown so that when inserted in place it will spring 80 into proper position and naturally tend to retain such position until positively removed by any desired means. The strap 15 passes between the body of the buckle and this plate 16 and is held securely owing to 85 the provision of a series of teeth 19 formed on the edge of the plate toward the locking bar, these teeth being inclined toward the front of the buckle so as to bite into the 90 strap.

A very important feature is the provision of means for preventing the buckle from slipping up beyond the waist band of the trousers in connection with which it is worn. In carrying out this feature I provide the lower flange 11 with an upward extension 20 formed with a notch 21 which extends downwardly from its upper edge and which is designed to be engaged upon 95 the top button at the front of the trousers.

In Figure 5 I have shown a slightly modified form in which this trouser engaging element is omitted, the structure being however the same in every other particular.

In the use of the device, after the belt or 110

strap is placed about the waist, in case it is designed for this purpose, or after it is placed about anything else which it is desired to hold, the free end of the belt strap 5 is inserted between the rear side of the end which is secured to the buckle, and the lock bar 13, the free end passing over the flange or apron 14^b. The free end of the belt strap is then pushed along until the proper tightness is had, whereupon any tendency toward slipping will be prevented owing to the fact that the lock bar 13 will be urged into the ends of the slots nearest the plate portion of the buckle, this of course resulting in a firm clamping action so that the greater the pull tending to loosen the belt the greater will be the clamping action of the lock bar. Owing to the fact that when the belt is applied, both ends are in engagement, it will be seen that there will be a greater degree of friction tending to hold the parts together than in the ordinary construction. The use of the trouser engaging extension has already been explained and 20 further description is therefore unnecessary.

While I have shown and described the preferred embodiment of the invention it is of course to be understood that I reserve the right to make such changes in the form, 25 construction and arrangement of parts as will not depart from the spirit of the in-

vention or the scope of the subjoined claims.

Having thus described my invention I claim:

1. A belt buckle comprising a frame formed from a single piece of resilient metal and including a body portion having side flanges defining a channel for the reception of one end of a belt, one end of the body being deflected rearwardly to define an abutment for the end of the belt, and a resilient plate located at the back of the belt and formed at its ends with lugs received within slots in said flanges, said plate having one edge toothed for penetrating engagement with the belt, and means for holding the other end of the belt. 40

2. A belt buckle comprising a body member having side flanges defining a channel for receiving one end of a belt, said flanges being formed with slots, an abutment at one end of the body engageable by one end of the belt, and a spring plate formed at its ends with lugs received within said slots, the plate having one edge provided with laterally deflected teeth for penetrating engagement with the belt, said plate being bowed, and means for holding the other end of the belt. 50

In testimony whereof I affix my signature.

WILLIAM M. MYERS.
